UNITED STATES PATENT OFFICE.

GEORGE D. WHITE, OF PORT ARTHUR, TEXAS, ASSIGNOR TO THE TEXAS COMPANY, OF NEW YORK, N. Y., A CORPORATION OF TEXAS.

PUMP.

Application filed February 12, 1923. Serial No. 618,432.

This invention relates particularly to pump mechanism adapted for handling fluids at high temperatures.

Difficulty has been experienced in providing pumps capable of operating successfully on highly heated fluids. It has been found difficult to keep the pump liner properly lubricated at high temperatures with the result that rapid deterioration of the pump mechanism usually accompanies the attempt to pump hot fluids with existing types of pumps. Moreover, it has been found practically impossible to maintain the stuffing boxes and bearings at a sufficiently low temperature to insure that the packing material and bearings will function properly. This defect has been especially detrimental when employing high pressures with the high temperature since the application of heat has caused the packing material to be readily permeable by the hot fluid with the result that leakage occurs under high pressures.

The primary object of my invention is to avoid these difficulties and to provide pump mechanism adapted for efficiently and economically handling fluids at high temperatures.

The pump constituting my invention preferably assumes the form of opposed helices mounted on a shaft coaxial with the pump cylinder and having a port intermediate the helices and other ports at the ends of the cylinder beyond the helices, the arrangement being such that the fluid to be pumped may be admitted by means of the central port and conveyed by the spirals to outlet ports at the ends of the cylinder, or the end ports may constitute the inlets of the pump and the intermediate port the outlet. By providing opposed helices on a common shaft so that the flow of fluid through the chamber is not all in the same direction it is possible to materially reduce the thrust action on the shaft to which the screw type pumps are generally subjected.

Specific objects of the invention that may be mentioned are: to reduce the number of stuffing boxes from that usually required in pumps employing the screw type principle and to provide means for maintaining the stuffing box and bearings of the pump shaft in a relatively cool condition.

Other objects as well as the particular advantages of the invention will become ap-

parent from the following detailed description thereof, reference being had to the accompanying drawings wherein:

Figure 1 is a longitudinal section of an apparatus constructed in accordance with the invention and constituting an embodiment thereof.

Figure 2 is a longitudinal section of a modified form of the invention.

In the example of the invention illustrated in Figure 1 a pump casing or cylindrical member 10 is provided within which is coaxially mounted the pump shaft 11. The pump casing is fitted interiorly with a liner 12 composed of cast iron or other suitable material. The shaft 11 carries opposed helices 13 and 14. In the central portion of the pump chamber intermediate the opposed helices 13 and 14 one or more ports 15 are provided and at the ends of the pump chamber beyond the helices one or more ports, as 16 and 17, are provided. It will be observed that the action of the pump is reversible, the port 15 and the ports 16 and 17 serving either as inlets or outlets, as may be convenient or desirable. In the apparatus illustrated the shaft is shown as having a right-hand spiral 13 and a left-hand spiral 14 and assuming that the shaft is rotated in a clock-wise direction it is apparent that the operation of the spirals would be such that the ports 16 and 17 would serve as inlets and the port 15 as an outlet. The action may be reversed either by changing the direction of rotation of the shaft 11 or by changing the helices mounted on the shaft. The port 15 is shown as communicating with a pipe 18. The ports 16 and 17 communicate with a manifold 19 through pipes 20 and 21, respectively, and the manifold pipe leads to a conduit 22.

At one end of the cylinder 10 a stuffing box for the shaft 11 is provided which may assume the form of a box 23, packing material 24, and a gland or follower 25. The end of the cylinder may be threaded, as shown, for the attachment of a flange 26 and the stuffing box secured thereto at the end of the cylinder by means of bolts 27, as illustrated.

Adjacent the other end of the shaft is a bearing 28. This bearing is preferably made in the form of a disc fitted loosely in the cylinder 10 and provided with a plurality of openings 29 for the passage of fluid. The bearing end of the cylinder may be closed by

means of a cap or plate 30 which may be secured by means of bolts 31 to a flange 32 threadedly attached to the end of the cylinder. As clearly shown in the drawing the bolts 27 and 31 may also serve to attach the pump to brackets or supporting members 33.

At each end of the pump chamber adjacent the stuffing box and bearing for the shaft are cooling chambers 34 and 35. In the example of the invention thus illustrated the shaft 11 is shown as formed with radial discs 36 and 37 which constitute baffles preventing the hot fluids in the pump chamber from gaining access to the bearing and stuffing box and constituting partitions between the cooling chambers 34 and 35 and the pump chamber proper. In the example shown it is contemplated that the fluid admitted to the chambers 34 and 35 is supplied from the pump chamber, the diameter of the baffles 36 and 37 being such that no material abrasive action will occur between them and the liner 12 with the result that fluid may seep through from the pump chamber to the cooling chambers. If desired, the baffle plates 36 and 37 may be attached to the pump liner 12 instead of to the shaft 11. It is apparent that any fluid seeping into the chambers 34 and 35 will be maintained therein at a lower temperature than that of the hot fluids passing through the pump chamber. If desired, extraneous cooling fluid may be positively introduced to the chambers 34 and 35; when the hot fluid handled by the pump possesses no lubricating qualities it is generally desirable to admit a fluid lubricant into the chamber 35 in order to properly lubricate the bearing 28. When handling petroleum oils or other fluids that have lubricating qualities it is ordinarily unnecessary to admit an extraneous lubricant into the chamber 35 and reliance for lubrication may be placed on the seepage of fluid into this chamber from the pump chamber.

The modified form of the invention illustrated in Figure 2 is intended particularly for pumping at high pressures. The pump casing is shown as comprising a pair of opposed flaring chambers 40 and 41 which converge at 42 to form a zone of restricted cross section. The shaft 43 is co-axial with the chambers 40 and 41 and carries opposed, tapered helices 44 and 45 adapted to cooperate with the flaring walls of the pump chambers 40 and 41. In order to build up high pressures in the pump outlet the inlet ports, as 46, are preferably positioned at the large end of the chambers and the outlet, as 47, placed at the restricted zone 42 marking the point of communication between the pump chambers. It is apparent that with the helices arranged so as to draw fluid from the large ends of the chambers 40 and 41 and conduct it into the outlet 47 that a high degree of pressure may readily be obtained.

The shaft 43 is preferably made adjustable in length. Thus the shaft may be constructed in two sections united by an adjustable collar 48. Abrasion between the helices and the cooperating flaring walls of the pump chamber will cause more or less wear, and in order to compensate for this the shaft is made adjustable in length so that the helices may be kept in proper contact with the flared chambers. The shaft is provided with a stuffing box 49 and a bearing 50, and may carry baffles 51 and 52, respectively, adapted to prevent heated fluids from coming in contact with the stuffing box and bearing.

When pumping gases it is desirable to supply a lubricant to the pump chamber. Thus the outlet line may terminate in a lubricant trap 53 provided with pipes 54 leading to the chambers 40 and 41. The action of the rotating screws will tend to keep the lubricant about the tapered walls of the chambers. A certain amount of the lubricant will be forced through the outlet 47 but it will be caught in the trap 53 and the pressure obtaining therein will feed the lubricant back to the chambers 40 and 41 through the lines 54.

If desired the action of the pump may be reversed either by changing the direction of rotation of the shaft 43 or by altering the helices. Likewise the flared chambers may be arranged with the point of convergence at the large ends thereof instead of at the small ends as illustrated.

Apparatus of preferred form and construction has been illustrated and described for the purpose of showing a way in which this invention may be used but the inventive thought upon which the application is based is broader than the illustrative embodiment thereof and I, therefore, intend no limitations other than those imposed by the appended claims.

What I claim is:

1. In a pump, a cylindrical casing, a shaft mounted longitudinally of said casing, a stuffing box for said shaft at one end of said casing, a bearing for said shaft at the other end of the casing, a fluid cooled chamber at each end of the cylinder adjacent said stuffing box and bearing, respectively, opposed helices on said shaft and ports arranged in the casing intermediate said helices and at the outer ends of same.

2. A pump comprising a casing, a shaft co-axial with and extending through said casing, a stuffing box for the shaft at one end of the casing, a bearing at the other end, opposed helices on said shaft and baffles interposed on the shaft between the helices and the stuffing box and bearing, respectively.

3. A pump comprising an elongated casing having a plurality of spaced ports intermediate its ends, a shaft coaxial with and ex-

tending through said casing, opposed helices disposed on said shaft between the ports, and means mounted on the shaft and forming substantial seals with the walls of the casing 5 between the ports and the ends of the casing and forming cooling chambers at the ends of the casing.

4. A pump for hot liquids comprising an elongated casing having a plurality of spaced 10 ports intermediate its ends, a shaft coaxial with and extending through said casing, a stuffing box in the casing for one end of the

shaft, a bearing for the shaft in the opposite end of the casing, opposed helices disposed on said shaft between the ports, and means 15 mounted on the shaft between the ports and the ends of the casing forming cooling chambers at the ends of the casing for protecting the stuffing box and the bearing from direct contact with the hot liquid being pumped. 20

In witness whereof I have hereunto set my hand this 29th day of January, 1923.

GEORGE D. WHITE.
